(57) **CLAIM**

The ornamental design for a sensor signal receiver, as shown and described.

DESCRIPTION

FIG. 1 is a perspective view of a sensor signal receiver showing our new design;

FIG. 2 is a front elevation view thereof;

FIG. 3 is a back elevation view thereof;

FIG. 4 is a right elevation view thereof;

FIG. 5 is a left elevation view thereof;

FIG. 6 is a bottom plan view thereof; and

FIG. 7 is a top plan view thereof.

FIG. 8 is a perspective view of an alternate embodiment of a sensor signal receiver showing our new design;

FIG. 9 is a front elevation view thereof;

FIG. 10 is a back elevation view thereof;

FIG. 11 is a right elevation view thereof;

FIG. 12 is a left elevation view thereof;

FIG. 13 is a bottom plan view thereof; and,

FIG. 14 is a top plan view thereof.

The broken lines depict portions of the sensor signal receiver that form no part of the claimed design.

1 Claim, 8 Drawing Sheets
